CLEO G. SHUMAN, OF CHICAGO, ILLINOIS, ASSIGNEE TO GYP STEEL PRODUCTS COMPANY, OF CHICAGO, ILLINOIS, A CORPORATION OF MISSOURI.

BUILDING STRUCTURE AND PLASTER-BOARD-ANCHORAGE MEANS.

1,308,199.

Specification of Letters Patent. Patented July 1, 1919.

Application filed April 9, 1917. Serial No. 169,862.

To all whom it may concern:

Be it known that I, CLEO G. SHUMAN, a citizen of the United States, and a resident of Chicago, in the county of Cook and State 5 of Illinois, have invented a certain new and useful Improvement in Building Structures and Plaster-Board-Anchoring Means, of which the following is a description, reference being had to the accompanying drawing, which forms a part of my specification.

My invention relates to building structures which are, in part, made up of blocks or plaster-boards placed end for end in the same plane and form a foundation for a 15 finish surface of plaster or other material, in lieu of a lath foundation.

The invention is more especially adapted to what is known as a furred ceiling which is formed with what are known as plaster-boards secured to an overhead concrete structure or floor; the invention contemplating means whereby the plaster-boards are anchored or attached in place beneath the overhead floor or concrete structure, and 25 also means whereby an air cell or space is provided intermediate of the concrete structure and the plaster-boards, which will permit proper circulation of air between the overhead concrete floor and the furred ceiling, to enable the proper drying of the concrete and at the same time also eliminate the possibility of discoloration or "marking" of the plaster applied to the plaster-boards, encountered in plaster-board ceiling 30 as heretofore constructed.

The invention is illustrated as embodied in a furred ceiling structure, although it is evident that the same may be applied to side wall constructions; and the advantages of 40 the invention will be more fully and readily comprehended from the following detailed description of the exemplification shown in the accompanying drawing, wherein:

Figure 1 is a bottom view in perspective, 45 of a portion of an overhead structure or floor, shown in section, illustrating portions of the fastening means embedded in the concrete, with the form-work or planking still in place, prior to the application of the 50 plaster-board to which the plaster is subsequently applied.

Fig. 2 is a similar view on an off-set line, 55 with the form-work or planking removed, my improved spacing and board-fastening means shown in place; portions of plaster-

boards secured thereto and a partial coating of plaster applied.

Fig. 3 is a detail view in perspective of the spacer and plaster-board securing member. 60

Fig. 4 is a detail perspective view of the spacer fastening member.

In the particular exemplification of the invention chosen for illustration, the usual form-work or planking 10, for an overhead 65 floor or covering (see Fig. 1) are first put into place and supported in any suitable manner. The form-work is then supplied with properly spaced domes 11, of any suitable material, for example sheet metal. The 70 domes are placed upon the form-work or planks and disposed in continuous rows at suitable intervals apart, throughout the entire floor or overhead concrete structure. In the drawing, the domes 11 are preferably 75 illustrated as of sheet metal, so arranged as to provide intervening spaces to be filled in by the concrete 12, which is applied to the desired thickness across all of the domes and the intervening spaces and the resultant 80 concrete beams thereby obtained. It will be understood, however, that my invention is equally as well adapted for use in connection with what is known as the slab construction of concrete floor, and I do not 85 wish to be understood, therefore, as limiting myself to the particular form of concrete construction, illustrated in the drawing.

After the respective domes have been arranged in the continuous manner, shown in 90 the drawing, my improved anchoring means or spacer-holder is then put into place, intermediate of adjacent rows of domes, and at proper intervals apart in a continuous 95 row before the concrete is poured. The fastening means in question preferably comprises a bent wire member 13, shown in detail in Fig. 4. The member is preferably bent in the angular U-shape manner so as to provide the two parallel portions or legs; 100 one leg 13^a being straight throughout, of greater length and terminating in a point adapted to pierce the form-work or planks 10. The other leg 13^b is of any desired length but less than the length of leg 13^a, 105 and preferably terminates in a stop or shoulder, shown formed by bending the end as at 13^c, see Fig. 4. The leg 13^b, with its bent end 13^c, not only provides a stop which determines the extent to which the member 110

may be driven in the form-work 10, but, in connection with the portion intermediate of the legs 13^a and 13^b, provides a concrete-receiving loop, which will hold the member 5 firmly against any possible withdrawal after the concrete has become "set," as shown in Figs. 1 and 2. It is understood, of course, that a suitable number of anchoring means or members are driven at predetermined 10 spaced intervals apart, determined by the width of the plaster-boards intended to be used; being arranged in substantially straight rows intermediate of adjacent domes prior to the pouring of the concrete, so as to locate 15 the fastening means substantially at the longitudinal center line of the resultant beams.

After the anchoring elements have been put into place, as above described, the usual reinforcing rods, shown at 14 in Figs. 1 and 20 2, are then laid on the form-work or planking, preferably at equi-distances from the fastening means and the domes, after which the concrete is poured onto the form-work or planking and across the domes to a sufficient depth or thickness so as to embed the 25 domes and the aforementioned fastening means.

As soon as the concrete has become sufficiently "set," the form-work or planking 30 is then removed by withdrawing the same from the fastening members or means, which leaves the end of the leg 13^a of the respective members to project or depend from the beam-portions of the concrete or 35 overhead construction to a predetermined extent.

The projecting shank or leg 13^a of the various anchoring members 13 are intended to receive the combined spacing members 40 and clips 15. The members 15 are preferably made of a rectangular piece of sheet metal along the longitudinal center line into a V-shape channel formation, as shown in perspective in Fig. 3, with the longitudinal 45 sides disposed laterally outward, as shown at 16 in Fig. 3. These sides are adapted to come into contact with the concrete beams, or the sides of the domes, as shown in Fig. 2; the combined spacers and clips being intended 50 to be arranged transversely of the beams, as shown. The apex or bottom of the V-portion of each member 15 is provided preferably at the center with a longitudinal slot 17 through which the leg 13^a of the 55 anchoring member 13 is intended to extend. The protruding end of each leg, namely the portion which extends below the combined spacer and clip 15, is bent over, as shown at 18 in Fig. 2, thereby firmly holding the 60 combined spacer and clip 15 in place against the bottom of the beam.

The longitudinal sides 16 of the combined spacer and clip are both slit from opposite ends of the clip, as shown in Fig. 3, so as to 65 provide the flexible prong-portions 19 and

20; which, after the clips have been applied in place, are intended to be bent downwardly at right angles to the longitudinal sides, as shown in Fig. 2, and in Fig. 3

here one of the prongs, to wit 19, is shown 70 in dotted lines bent into position; it being understood that all of the prongs are bent downwardly before the plaster-boards are applied. It is understood, of course, that a combined spacer and clip member 15 is applied to each fastening means or anchor 13, so that one or more clips are provided for every plaster-board section, as shown in Fig. 2; the fastening means and combined spacers and clips being provided at predetermined 75 intervals apart commensurate with the width of the plaster-boards which are shown at 21. The plaster-boards 21 are of a length sufficient to extend from beam to beam and rest on the apex or downwardly 80 presented portion of the member 15. The downwardly bent prongs 19 and 20 of the respective clips at both ends of the boards, are intended to extend downwardly between the abutting ends of the respective board-sections. After a plaster-board section has been properly placed, one prong of each clip, with which the section contacts, is bent over the adjacent end of the board, that is, one 85 prong, as for example prong 19, has its end 90 bent beneath the board-section located on one side, or to the right of the clip while the other prong 20 has its end bent beneath the board-section adjacent and located to the left of the clip, as shown in Fig. 2; in 95 other words, the prongs of each spacer and clip are intended to hold the adjacent ends of the two board-sections, as clearly shown.

After all the spacing members or elements have been put into place and the sectional 100 plaster-boards 21 secured by the respective prongs of the different spacing members or elements, as shown in Fig. 2, the coating of plaster, indicated at 22 is then applied to the plaster-boards, entirely covering the bent 105 ends of the various clips. The invention 110 may have expression in somewhat different mechanical form without, however, departing from the spirit of my invention, and I do not wish to be understood as limiting 115 myself to the exact construction shown and described.

What I claim is:—

In a building structure of the class described, the combination of a structure 120 formed of hydraulically setting material, with a series of hook-shape fastening elements embedded in said hydraulically setting material, said elements being provided with elongated shanks adapted to protrude 125 from the hydraulically setting material, sheet metal spacer-members being throughout their lengths substantially V-shape in cross-section with the longitudinal edges disposed laterally outward adapted to rest 130

against the hydraulically setting material, said edges being slit from opposite ends of the members so as to provide flexible portions or tongues, while the apex portions of the members are adapted to project away from said hydraulically setting material, the apex portions being provided with openings at a point intermediate of the ends of the members adapted to receive the shanks of the respective hook-shape element, and sectional plaster-boards disposed between adjacent rows of fastening elements and supported at the ends on the spacer members, with the flexible tongue at one end of each spacer member bent about the end of one plaster-board, while the other tongue of each spacer member is bent about the abutting end of a second plaster-board.

CLEO G. SHUMAN.
